DESIGN FOR A WINE PITCHER

Vilhelm Hingelberg, Aarhus, Denmark

Application December 10, 1946, Serial No. 135,389

Term of patent 14 years

(Cl. D44—21)

To all whom it may concern:

Be it known that I, Vilhelm Hingelberg, a citizen of Denmark, residing in Aarhus, Denmark, have invented a new, original, and ornamental Design for Wine Pitcher, of which the following is a specification, reference being had to the accompanying drawing, forming a part thereof, in which:

Fig. 1 is a top view of the wine pitcher showing my new design;

Fig. 2 is a side elevation thereof; and

Fig. 3 is a side elevation taken at right angles to Fig. 2 and showing the article from the right of Fig. 2.

I claim:

The ornamental design for a wine pitcher, as shown.

VILHELM HINGELBERG.
